UNITED STATES PATENT OFFICE.

JOSEPH F. ROBINEAU, OF CHICAGO, ILLINOIS, ASSIGNOR TO THE DEARBORN COMPANY, OF CHICAGO, ILLINOIS, A CORPORATION OF ILLINOIS.

CARD TABLE.

Application filed May 26, 1923. Serial No. 641,565.

The main object of my invention is to provide a card table of improved construction.

Other objects of my invention are to provide an improved card table which has a detachable top; which is collapsible; and which has improved means for locking the several parts of the table in extended positions relative to each other.

10 Other objects of my invention will become apparent as the detail description progresses, reference being had to the accompanying drawings, wherein

15 Fig. 1 is a vertical longitudinal section through a card table embodying the novel features of my invention, the legs thereof being shown in positions wherein they support the frame and top of the table.

20 Fig. 2 is a section taken on the same line as Fig. 1, the table having been collapsed.

Fig. 3 is a fragmentary bottom plan view of my improved card table, the table being shown in a collapsed condition.

25 Fig. 4 is an enlarged fragmentary section through my improved card table, the section being taken on the same line as Fig. 1.

Fig. 5 is a section taken on line 5—5 of Fig. 4.

30 Fig. 6 is a fragmentary detail view of one of a plurality of hinged braces, which form parts of my improved card table, and which are provided with means for locking them in a rigid condition.

Fig. 7 is a section taken on line 7—7 of 35 Fig. 6.

Fig. 8 is a section taken on line 8—8 of Fig. 2, and

Fig. 9 is a fragmentary detail view illustrating another form of means for locking the hinged members in a rigid condition.

Similar characters of reference designate similar parts throughout the several views.

Referring for the present to Figs. 1, 2 45 and 3 of the drawings, the reference character 10 designates a rectangular frame to which is pivotally secured a plurality of legs 11 which are adapted to be held in positions wherein they support the frame 10, as shown in Fig. 1, or to be swung into positions wherein they lie adjacent and parallel to the top 12 resting upon the frame, as shown in Figs. 2 and 3. The frame 10 is rectangular in form and com-

is provided with a shoulder 14 adapted to receive and support a marginal portion of the top 12 which has its top surface substantially flush with the top surface of the frame. One of the legs 11 is pivotally secured to each of the bars 13 by a bolt 15, the leg being spaced from the bar by a collar 16 through which the bolt passes, and which is interposed between the bar and the leg. The inner end of each bolt 15 is preferably supported in an angle bracket 17 which is rigidly secured to one of the bars 13 abutting the particular bar 13 through which the bolt passes.

Each of the legs 11 is adapted to be held in its extended or supporting position relative to the frame 10 by means of a hinged brace 18 comprising a plurality of links 19 and 20, each of the links having one of its ends pivotally secured to an end of the other link by a rivet 21. As shown in Figs. 4 and 5

each link 19 is pivotally secured to one of the bars 13 by a wood screw 22, and each link 20 is pivotally secured to a leg 11 by a wood screw 23. When the card table is collapsed, the hinged braces 18 are adapted to fold into the positions shown in Figs. 2 and 3. But when the hinged braces are in the positions shown in Figs. 1, 4 and 5, the rivet 21 of any one of the hinged braces cannot be moved in a direction away from the pivotal axis of its associated leg 11, as each link 20 extends beyond its associated rivet 21 a distance sufficient to permit a stop 24 to be formed therein, which is adapted to 80 engage a shoulder 24^a formed in the associated link 19. I have applied the reference character 20^a to the extensions of the several links 20, the aforementioned stops 24 being formed in these extensions 20^a. It is apparent that the hinged braces 18 will hold the legs 11 in their extended or supporting positions and that the hinged braces may be quickly and easily folded into the positions shown in Figs. 2 and 3. But as the hinged braces 18 may be inadvertently collapsed by the players seated at the card table, I find it desirable to provide means for locking the links 19 and 20 of each hinged brace 18 against angular displacement relative to 90

each other when the table is in use.

To lock the links 19 and 20 of each brace 18 against angular displacement relative to the rivet 21 which pivotally secures the links, I provide a locking sleeve 25, slidably 100

55 comprises a plurality of bars 13, each of which 110

mounted upon the link 19. One end of each of the locking sleeves 25 is adapted to fit snugly around its associated link 19, and the other end of the sleeve is adapted to fit snugly around both the link 19 and the extension 20^a of the associated link 20 when the sleeve is brought into the position relative to the links 19 and 20 shown in Figs. 4, 5 and 6. It will be readily understood that when the table is to be collapsed, the sleeves 25 may be slipped back from the positions wherein they engage the several extensions 20^a of the links 20.

In Fig. 9 I have shown another form of locking sleeve, which is designated by the reference character 25^a. The locking sleeve 25^a is slidably mounted on a link 19^a forming part of a hinged brace 18^a having a second link member 20^b. The link members 19^a and 20^b are pivotally secured to each other by a rivet 21^a. The link 20^b has an extension 20^c which is provided with a notch 20^d adapted to receive a tongue 25^b formed integral with the locking sleeve 25^a. The hinged brace 18^a is of course identical with any of the aforementioned hinged braces 18, with the exception of the notch 20^d cut in the link 20^b. The locking sleeve 25^a is employed to lock the links 19^a and 20^b against angular displacement relative to the rivet 21^a when the card table, of which the hinged brace 18^a forms a part, is in use, the locking sleeve being slipped back to withdraw the tongue 25^b from the notch 20^d, when the table is to be collapsed.

I will now describe the top 12 of my improved card table and means whereby I detachably secure the top 12 to the frame 13.

I prefer to make the top 12 of paper, fiber or the like, and to provide the top with a cover 26 of leatherette or a similar material. The cover 26 is drawn tightly over the upper surface of the top 12 and also around the edges of the top, so that its marginal portions may be glued or otherwise secured to the under surface of the top, as indicated by the reference character 27.

As shown in Figs. 1, 2, 3 and 8, the frame 13 is provided with a centrally disposed cross bar 28 which has its ends resting in recesses 29 formed in two of the bars 13, the cross bar 28 being rigidly secured to these bars by wood screws 30. The advantage of this construction over the usual construction is that the central portion of the top is supported and therefore will not become dished.

To detachably secure the top 12 to the several bars 13 and the cross bar 28 of the frame 10, I provide a plurality of bent clips 31 each of which is pivotally secured to the under surface of the top 12 by means of a rivet 32 passing through the top and having

the head at its upper end concealed by the cover 26. The portions of the top 12 which immediately surround the several rivets 31 are reinforced by washers 33, a washer 33 being provided for each of the rivets. The free ends of the clips 31 are adapted to be swung into positions wherein they engage grooves 34 formed in the bars 13, or wherein they engage grooves 35 formed in the cross bar 28.

In the event that the top 12 becomes warped, or in the event that the cover 26 becomes worn, the top 12 may be easily removed from the frame 10 by swinging the clips 31 into positions where they do not engage the grooves 34 and 35. A new top, identical in construction to the old top, may then be placed in the frame 10 and detachably secured to the frame by means of its clips 31.

The above described means for detachably securing the top 12 to the frame 10 is particularly adapted to be used in connection with a top having a cover affixed thereto in the manner described, as the clips may first be secured to the top and the cover afterwards applied thereto, thus preventing injury to the cover and obtaining concealment of the means whereby the clips are secured in place.

I am aware that changes in the form, construction and arrangement of parts may be made without departing from the spirit and without sacrificing the advantages of the invention and I reserve the right to make all such changes as fairly fall within the scope of the following claim.

I claim:

A card table comprising a rectangular frame having a plurality of bars connected at their ends, a shoulder on said bars at the inner edge of the top thereof, a centrally disposed cross-bar connected at its ends to opposite bars of the frame and having its top in the plane of said shoulder, said frame bars having grooves in their inner sides below the shoulder and said cross-bar having grooves in its opposite sides, a top arranged to rest upon the shoulder and flush with the top of the frame, clips pivoted to the inner side of the top and adapted to engage the grooves in the bars and cross-bar to detachably fasten the top to the frame, a collar and a bracket fixed to said frame, a leg pivoted to said collar and said bracket, a two-part hinged brace having its upper end pivoted to the frame and its lower end pivoted to said leg, a locking sleeve slidable on said brace and having unrestricted movement thereon to lock the brace in extended position, and a stop for holding the sleeve in locked position.

JOSEPH F. ROBINEAU.
